UNITED STATES PATENT OFFICE.

JAMES LIGGETT, OF CHICAGO, ILLINOIS.

CLOTHES WRINGER.

Application filed September 26, 1923. Serial No. 664,874.

This invention relates to a clothes wringer which is so designed as to guard against injury to the clothes which is sometimes occasioned by a winding up of the fabric or portions thereof upon one of the compression rollers, and is also designed to facilitate the feeding of the clothes to the point of compression. The invention embodies the use of contacting endless belts, preferably of rubber, which are interposed between the compression rollers, so that the wringing is effected by the action of the belts rather than by immediate contact of the rollers themselves.

In this arrangement there is a gradual rather than an abrupt advance of the fabric to the compression point, which guards against injury to the hand of the operator, guards against tearing or fraying of the fabric, and provides for the discharge of the water in a suitable and convenient manner.

In the drawing:—

Figure 1 is an end view partially in section, showing the features of the present invention; and

Fig. 2 is a side view of one end of the wringer, the other end being broken away.

The wringer, as a whole, comprises a pair of end frames 10 each of which is preferably of a configuration providing upper arms 11, lower and more elongated arms 12, and a connecting neck 13. The arms are shown as extending obliquely from the neck portion of each end frame, the upper and lower arms affording mountings for a pair of upper rollers 13 and a pair of lower rollers 14 arranged in spaced relation, as shown. Each end frame has outwardly extending therefrom on each side of the center a vertical flange 15, and the wall of the frame intermediate the flanges is perforated to provide an upper slot 16 and a lower slot 17.

The upper slot carries a slidably mounted half bearing block 18 opening downwardly, and the lower slot carries a half bearing block 19 opening upwardly. The upper bearing block serves as a journal mounting for a pintle 20 on the end of a compression roller 21 preferably formed of comparatively hard rubber of a character customarily employed in the construction of clothes wringers.

The upper roller 21 co-acts with a similar lower roller 22 provided with a pintle 23 which extends outwardly through the slot 17, and is preferably squared at its end 24

to receive a handle 25. The lower bearing block 19 affords a journal mounting for a pintle 26 of a central idle roller 27 located immediately below the lower compression roller, as shown. It will be understood that the arrangement is duplicated at each end of the machine with the exception that at the far end of the machine it is desirable to provide intermeshing gears 28 on the pintles which carry the upper and lower compression rollers so as to positively drive both of these rollers when the handle is rotated.

The upper journal block 18 is backed by a coil spring 29 bearing against a slidable follower plate 30 contracted by a thumb-screw 31 entered through a bridge 32 so that the degree of compression between the rollers can be varied or regulated at the will of the operator. The idle rollers 13 and 14 are mounted upon pintles 33 each of which projects outwardly through an elongated slot 34 in the adjacent portion of the adjacent end frame, and each of the pintles near its outer end has rigidly mounted thereon a grooved disk 35 which is surrounded by a ring-shaped ball-race 36, ball bearings 37 being interposed to reduce friction.

It will be understood that the slots 34 merely afford the necessary clearance for the pintles, and that the parts are journaled on the ball bearings constructed and located, as indicated. In order to provide for an in and out adjustment of the bearings, each of the ring-shaped ball-races is provided with a screw-threaded stem 38. The stems for the ball-races which support the lower rollers 14 are entered through outwardly extending lugs 39 formed on the lower arms of the end frames, and adjustment is effected by means of inner and outer jamb nuts 39 and 40 on opposite sides of the lugs. The stems for the upper ring-shaped ball-races are entered through the adjacent flanges 15 and locked in the manner heretofore described.

The two upper rollers 13, together with the upper compression roller, afford a mounting for an endless upper compression belt 41, while the two lower idle rollers 14, together with the central idle roller 27 and the lower compression roller in conjunction, afford a mounting for a lower endless compression belt 42. Each of the compression belts is preferably formed of relatively thick and compressible soft rubber which will possess sufficient elasticity to permit it to be

tensioned to the desired degree by adjustment of the idle rollers and possess sufficient compressibility to afford a soft yielding surface in contact with the clothes.

It will be observed that the two upper idle rollers are so disposed in relation to the upper compression roller that the upper endless compression belt will travel obliquely toward and from the compression point, and 10 likewise that the mountings for the lower compression belt will hold the latter obliquely elevated at its center point so that the two belts, in conjunction with one another, will subtend converging spaces on opposite sides of the compression rollers. It 15 will also be observed that the center idle roller is mounted to hold the lower turn of the lower compression belt in elevated relation at its center point and in contact with 20 the overlying lower compression roller.

In order to mount the wringer as a whole on the tub with which it is to be used, lugs 43 outstanding from the flanges 15 are provided at each end, which lugs are perforated 25 to receive screws or bolts adapted to secure the wringer to a pair of spaced uprights, not shown, and which are provided on the edge of the tub. In use, the turning of the handle will feed the upper and lower compression belts in converging relation toward one another, and the wet clothes are placed upon the lowermost belt and carried upwardly to the compression point. The convergence of 30 the two belts is gradual rather than abrupt, so that the compression will be gradually applied in a manner which will avoid tearing or fraying of the fabric, and will also tend to flatten down the buttons in such a manner as to prevent the same from being 35 torn off. The contact of the two belts will afford a firm and yet yielding compression for the clothes, and the water expressed therefrom will run down along the lower belt and back into the tub, it being understood 40 that the edges of the belts lie in close contact with the inner faces of the respective end frames.

The invention is one which provides for a suitable tensioning of the belts to effect a proper feeding of the clothes and for a regulation of the pressure applied at the point where the water is expressed. Although the invention has been described with considerable particularity, it is not the intention to strictly limit the invention to the details herein set forth, since the same may be modified without departing from the spirit of the invention.

I claim:—

In a clothes wringer, the combination of end frames in spaced relation to one another, upper and lower compression rollers mounted one above the other between center portions of the end frames, a pair of upper guide rollers on opposite sides of and above the interspace between the compression rollers and at substantially equal distances therefrom and mounted between upper outer portions of the end frames, a pair of lower guide rollers on opposite sides of and below the interspace between the compression rollers and at substantially equal distances therefrom and mounted between lower portions of the end frames and at a greater distance from one another than the upper guide rollers, an upper endless compression belt having lower turn portions inclined downwardly from the upper guide rollers and carried beneath the upper compression roller and around the upper guide rollers, a lower compression belt having upper turn portions inclined upwardly toward and over the lower compression roller and carried around the lower guide rollers, the end frames standing in close relation to the edges of the respective belts to furnish closely spaced side guides along the inclined portions of the belts, journal mountings for the ends of the respective guide rollers, and means for adjusting said mountings to slightly vary the distances between the respective pairs of rollers for taking up slack in the belts, substantially as described.

JAMES LIGGETT.
